[57] CLAIM

The ornamental design for a table top or similar article, as shown and described.

DESCRIPTION

FIG. 1 is a front elevational view of a table top or similar article showing my new design;

FIG. 2 is an end elevational view, the opposite end being a mirror image thereof; and

FIG. 3 is a top plan view of the table top or similar article;

The support structure depicted by means of dot-dash lines in FIGS. 1-3 have been shown for illustrative purposes only.

FIG. 2

FIG. 1

FIG. 3
